SHOCKPROOF BOTTLE CONTAINER

Mortimer B. Salkowitz, Brooklyn, N. Y.

Application February 26, 1947, Serial No. 731,002

3 Claims. (Cl. 229—90)

1

The present invention is concerned with a transportation package for an individual bottle.

It is among the objects of the invention to provide a transportation container of the above type which shall be substantially entirely of paper stock and which shall be substantially shock-proof by affording protection to the contents against breakage under the most severe impact to which such packages are likely to be subjected in rough handling during transportation, and which shall be of relatively low cost and attractive appearance.

In the accompanying drawings in which is shown one of various possible embodiments of the several features of the invention,

Fig. 1 is a view in longitudinal cross section through the complete package,

Fig. 2 is a dropped perspective view of the component elements of the container on a smaller scale, and

Fig. 3 is an enlarged fragmentary detail sectional view.

Referring now to the drawings, the protective container comprises an outer cylindrical or tubular casing or box 10 which outer casing or box consists of a base 11 and a tubular cover 12. Said elements of the outer casing are telescoped over a cushioning liner 13, the lower rim of the latter abutting the base and the rims of the base and cover abutting in the closed package, as shown.

The base and the cover are preferably of identical construction, except that the cover is desirably somewhat shorter than the base, as shown. The base comprises a tubular wall of relatively stiff paper tube stock of conventional type. Its end wall is preferably a disc 14 of sheet metal crimped as at 15 at its periphery about the lower rim of the base. For added stiffness, the outer rim 15 of the metal end wall is crimped against the outer wall of a cup formation 16 of said metal cup, thereby to compress the lower rim of the paper stock base therebetween.

The cushioning liner is preferably of composite construction in that it comprises a pair of paper stock tubes of the same type as those of the outer casing, though desirably of greater thickness and greater stiffness. The outer diameter of the inner tube 17 is smaller than the inner diameter of the outer tube 18 of the liner to define an annular space therebetween in which is lodged a sheet 19 of corrugated paper board completely encompassing the inner tube 17. The height of the cushioning liner is preferably somewhat less than the combined height of the

2

base 11 and cover 12 of the casing, as shown. Desirably the elements of the composite liner are adhesively connected together and the liner is also adhesively connected to the base 11 while the cover 12 is removably telescoped over the portion of the cushioning liner 13 that protrudes beyond the rim of the base 11.

Cushioning means are preferably provided against the sheet metal end walls of both the base and the cover. Each cushioning means preferably comprises a stack of discs 20 of corrugated paper board, each stack preferably lodged in a paper stock cup 21, the face of which is at the inside of the casing, while the rim 22 thereof is frictionally interposed between the rims of the corrugated discs 20 and the inner wall of the base 11 and the cover 12 respectively. If desired the cushioning discs 20 or the cup 21 or both may also be cemented or glued in place 20 within the base and cover respectively. The liner 13 as shown, engages the peripheral area of cushion cup 21 in the base 11.

The upper end of liner 13 may engage cushion cup 21 of the cover 12, but in the embodiment shown, it ends below said cushion cup and supports a bottle neck holder 23 spaced from the cover end wall. The bottle neck holder preferably comprises a shallow disc 23 of paper stock, centrally perforated at 24 for accommodating the neck of the enclosed bottle B and having a rim 25 snugly fitted over and embracing the inner tube 17 of the protective liner. The corrugated paper board element 19 of the liner affords space, as shown, to accommodate rim 25 of the bottle neck holder, and to this end said corrugated intermediate liner member may be correspondingly shorter than the inner liner tube 17.

Thus it will be seen that the entire container 40 is made of conventional paper tube stock, of paper stock cups, of corrugated paper board, and of two sheet metal end discs. The container is therefore of relatively inexpensive material and it is obviously easily assembled.

In use the packaged bottle B, usually a bottle of liquor, is adequately cushioned at its ends by the end cushions 20 and at its sides is securely encompassed by the cushioning liner 13 and the outer casing 10. The sheet metal end walls 16 stiffen the package materially against collapse or injury resulting from edgewise impact while the side wall structure 10, 11, 17, 18, 19 affords adequate stiffening and cushioning against lateral impact or pressure. The package of the 55 present invention with its contained liquor has

been subjected to much more severe tests than those encountered in transportation and has in every case afforded complete protection to its bottle contents. In fact bottles packaged in the container above described, when dropped from a height of 20 feet upon a concrete floor, remained intact, whether the impact was taken upright, on the side or on the end edge of the container.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention what I claim as new and desire to secure by Letters Patent of the United States is:

1. A shock-proof individual shipping container for bottled goods comprising an outer casing of conventional stiff paper tube stock, including a base having an end wall of sheet metal crimped thereto, a composite protective liner secured within said base, said liner comprising two tubes of conventional stiff paper tube stock defining an annular space therebetween, corrugated paper board in said space and encompassing the inner tube, said liner protruding substantially beyond the rim of the base, said casing including a cover of construction similar to that of the base and removably telescoped over the protruding part of the liner for rim to rim abutment against the base, and corrugated board cushions retained by and lodged against the inner faces of the respective sheet metal end walls of the base and the cover, the inner face of the base cushion being abutted by the end of the liner, each of said end cushions comprising a stack of discs of corrugated paper board and a paper stock cup with its face exposed to the interior and its rim snugly intervening between the rims of the respective stacks of cardboard discs and the inner wall of the base and cover respectively.

2. A shock proof individual shipping container for bottled goods comprising an outer casing of stiff paper tube stock having a base with an end wall of sheet metal crimped thereto, a composite protective liner secured within said base, said liner comprising two tubes of stiff paper tube stock defining an annular space therebetween,

corrugated paper board in said space and encompassing the inner tube, said liner protruding substantially beyond the rim of the base, a cover of construction similar to that of the base and removably telescoped over the protruding part of the liner for rim to rim abutment against the base, corrugated board cushions against the respective sheet metal end walls of the base and the cover, each of said end cushions comprising

10 a stack of discs of corrugated paper board and a paper stock cup with its face exposed to the interior and its rim snugly intervening between the rims of the respective stacks of cardboard discs and the inner wall of the base and cover respectively, and a bottle neck protector comprising a paper stock cup centrally perforated having a rim snugly encompassing the end of the inner tube of the protective liner, the corrugated paper board element of the liner being somewhat shorter than the inner tube to afford space for accommodating the rim of said cup.

15 3. A safety container for bottles or the like comprising a composite tubular liner sleeve including an outer tube of paper stock, an inner tube of paper stock, an interspacer of corrugated paperboard, the upper edge of which is below the upper edges of the outer and inner tubes, an outer casing comprising a base encompassing the lower part of the liner and secured thereto, a shallow 20 centrally perforated cup for accommodating a bottle neck, removably telescoped at its rim over the inner wall of the liner and accommodated in the space above the upper edge of the interspacer, a cover removably telescoped over the upper part 25 of said liner, said base and said cover each having a sheet metal disc end wall crimped thereto and cushioning discs against the respective end walls.
